UNITED STATES PATENT OFFICE.

R. D. GRANGER, OF PHILADELPHIA, PENNSYLVANIA.

HEATING APPARATUS.

Specification forming part of Letters Patent No. 22,642, dated January 18, 1859; Antedated November 24, 1858.

To all whom it may concern:

Be it known that I, RENNSLAER D. GRANGER, of the city and county of Philadelphia and State of Pennsylvania, have invented a new and useful Improvement in Heating Apparatus; and I do hereby declare the following to be a full, clear, and exact description of the same, reference being had to the accompanying drawing and to the letters of reference marked thereon.

My invention relates to an improvement in stoves or heaters in which an air chamber situated above the fire is used for receiving a supply of cold air below and discharging it in a heated state through an opening above, and my improvement consists in combining with the air chamber a separate chamber perforated with holes and having an independent communication with the external air, the second or supplementary chamber being so situated in regard to the first, that while it serves the purpose of effectually consuming the gases arising from the products of combustion it serves to protect the bottom of the general chamber from the injurious action of the fire.

In order to enable others to make and use my invention, I will now proceed to describe its construction and operation.

On reference to the accompanying drawing: Figure 1, is a vertical section of my improved heating apparatus. Fig. 2, a transverse, sectional plan (inverted) on the 1, 2 (Fig. 1).

A is the body of an ordinary coal stove, B the hollow base for receiving the ash pit, C the cap of the stove, D the fire pot, E the grate, F the fire-door, and I the pipe communicating with the chimney.

Although the stove illustrated forms a convenient portable design for applying my improvements in heating apparatus, various modified forms may be substituted.

In the interior of the stove I hang an air chamber G, the top of which passes through an opening in the cap C, there being a free access of air to the lower end of the chamber, through one or more passages a.

Adjacent to the under side of the chamber G and separated from the same, is secured an annular chamber H, which com-

municates with the external air through a small independent passage b. This annular chamber has a series of perforations on the under side.

A pipe communicating with an adjacent or upper apartment may be connected to the end of the chamber G, which projects through the cap, or this end of the chamber may be covered with a grating or register, so as to allow the heated air from the chamber to escape directly into the room in which the heater is situated. The air chamber G being situated but a short distance from the fire, becomes rapidly heated, and the air entering through the passages a, has a corresponding heat imparted to it, and escapes either through a register on the cap, to add to the heat imparted to the room by the radiation of the heater itself, or passes through pipes to any adjacent apartments. As the products of combustion rise, they are met by jets of heated air from the chamber H, which ignite the gases, and cause them to pass upwards, in the form of a flame, to the chimney. It will thus be seen, that the sides of the chamber G as well as the bottom, with the exception of the annular space obstructed by the chamber H, are completely exposed to the ignited gases, and that an extensive supply of heated air is obtained at the expense of a comparatively small amount of fuel.

The annular chamber H, besides serving the purpose of igniting the gases, also tends to protect the corners of the main chamber G from rapid destruction by the action of the fire. When the annular chamber itself becomes deteriorated by the action of the fire, it may be readily removed, and replaced by a new one.

In heaters of the larger class, I propose to use two or more chambers G, with a perforated chamber H attached to each.

I do not claim broadly an air chamber situated in a casing and exposed to the action of the fire within the same, as such a device has been heretofore used but

I claim and desire to secure by Letters Patent—

Combining the air chamber G with the separate perforated chamber H having an

independent communication with the air substantially as herein set forth, so that the said perforated chamber may serve the double purpose of consuming the gases arising from the ignited fuel and of preventing the rapid destruction of the bottom of the chamber G by the action of the fire.

In testimony whereof, I have signed my name to this specification before two subscribing witnesses.

RENSSELAER D. GRANGER.
